United States Patent

Des. 235,395
Patented June 17, 1975

235,395

CHAIR

Morris F. Fisher, Carmel, Ind., assignor to Futorian Corporation, Amsterdam, N.Y.

Filed Feb. 26, 1973, Ser. No. 336,127

Term of patent 14 years

Int. Cl. D6—01

U.S. Cl. D6—71

The figure is a perspective view of a chair illustrating my new design.

The back of the chair is conventionally plain while the side not shown is substantially identical to the side shown.

I claim:

The ornamental design for a chair, as shown and described.
